UNITED STATES PATENT OFFICE.

JAMES J. HARKINS, OF PITTSBURGH, PENNSYLVANIA, ASSIGNOR OF ONE-FIFTH TO
OTTO F. ORMAN, OF SANDY LAKE, PENNSYLVANIA.

PLUG-BAR MECHANISM FOR PIERCING MILLS.

Application filed July 3, 1924. Serial No. 724,024.

This invention relates to an improvement in plug bar mechanism used in seamless tube making processes, the invention being particularly adapted for cooperation with a 5 piercing mill of any usual or preferred type.

The invention is particularly designed for use in connection with a continuous seamless tube rolling mill of the type shown in my 10 joint co-pending application with O. F. Orman, Serial No. 341,931, filed December 2, 1919.

In the operation of forming seamless tubes, a billet is passed through piercing 15 rolls over a ball or plug carried on the free end of a long bar or rod whose opposite end is supported against endwise movement, that is, against the thrust of the oncoming shell, in a thrust bearing designed to allow 20 the plug bar to rotate with the rotative movement of the shell imparted to it by the action of the piercing mill.

Heretofore it has been the common practice to withdraw the plug bar from the 25 pierced shell after the piercing operation is completed.

The present invention has for its principal object to provide plug bar mechanism adapted to support the plug bar and receive the 30 pierced shell at the front end thereof in the usual manner, but which may be operated to enable the shell to be passed off the opposite end of the plug bar, through the thrust bearing without removing the plug bar from operative position, so that ingots may be 35 pierced in rapid succession, a feature particularly valuable where continuous rolling is sought, as described in the above noted application, but not necessarily confined to 40 use in continuous mills.

Further important objects are to provide, in combination with the thrust bearing mechanism per se, a receiving and pushing mechanism for simultaneous cooperation 45 therewith. These and other objects and advantages are attained by my invention, which may be readily understood by reference to the accompanying drawings, in which:

50 Fig. 1 is a plan view of the thrust bearing mechanism assembly, without the auxiliary pusher mechanism;

Fig. 2 is a longitudinal section through

the mechanism shown in Fig. 1, showing the auxiliary pushing mechanism;

55 Fig. 3 is a transverse section in the plane of line III—III of Fig. 1;

Fig. 4 is a similar section in the plane of line IV—IV of Fig. 1, showing the plug bar engaging means in closed position;

60 Fig. 5 is a similar view showing the plug bar engaging means in open position;

Fig. 6 is a detail view of the jaw controlling and operating means;

Fig. 7 is a section in the plane of line 65 VII—VII of Fig. 6; and

Fig. 8 is a section in the plane of line VIII—VIII of Fig. 1.

The invention is designed for use in connection with a piercing mill of any commercial or preferred type, and this, therefore, has not been shown in the drawings.

In the drawings, X designates a suitable foundation on which a base member 5 is mounted, this base member having platforms 6, 7 and 8 stepped one below the other, respectively.

Slidably mounted on platform 6 is a jaw-carrying head or frame 9, to which piston rod 10 connects, the piston rod entering a hydraulic or pneumatic cylinder 11 on the lowermost platform 8. By suitable control of this cylinder, control means not being shown but being of the usual type, the head 9 may be reciprocated toward and 85 away from the forward end of the base, the head being shown in Figs. 1 and 2 in its foremost position.

On the extreme forward end of the base 90 is a stand 12 having a recess 13 therein in which sets a slidable wedge 14 cooperating with an inclined surface 15 on the under side of a saddle shaped member 15^a, in which the forward ends of guide plate 16 are supported. A screw 17 provides for the longitudinal adjustment of wedge 14, thus enabling the saddle to be adjusted vertically to raise or lower the guides. A heat retaining hood may be provided at 19 and another at 20.

100 The plug bar is designated A, and carries the removable plug or ball B of usual construction.

105 Supported at each side of frame or head 9, near the bottom thereof, are shafts 21 and 21^a, each having lever arms 22 and 22^a re-

spectively carried thereon. The upper ends of levers 22 pivotally connect at 23 with transverse slide blocks 24 (see Fig. 8) slidably carried in guides on the top of head 9 and which support longitudinal plug bar 5 engaging jaw 25. The upper ends of levers 22^a pivotally connect at 23^a to similar blocks 24^a carrying cooperating jaw 25^a.

Secured to shaft 21 is a lever 26 whose outer end engages piston rod 27 operated through cylinder 28 pivotally supported on lateral bracket 28^a secured to head 9. Lever arms 29 and 30 pivotally connected at 31 connect shafts 21 and 21^a. When piston rod 27 is moved downwardly, it being shown in its uppermost position, shafts 21 and 21^a are rocked in opposite directions, thereby opening jaws 25 and 25^a. The jaws are closed upon reverse movement of the piston rod 27.

Mounted on piston rod 10 is an arm 32 which carries hood 33 and guide support 34 which obviously will move with the head 9.

Arched over the cylinder 11 and secured to the base 5 is a support 35 having a transverse channel 36 at the top thereof, in which is a fixed lower wedge 37 and a transversely movable wedge 38. On the upper wedge rests a depending rib of a block 39, to which are secured the guide strips 16. The strips are sloped downwardly toward each other to form a trough.

Block 39 forms part of a supporting frame 40 whose other end is similarly supported at two other points on wedge blocks 41-42 similar to 37-38 in the base member 43. The upper wedge blocks may be shifted transversely to raise or lower the frame through screws 44.

The frame 40 carries troughed feed rollers 45 and troughed guide sections 46. The feed rollers are all driven through miter gears from a longitudinal shaft 47 which is in turn driven through reduction gearing 48 by motor 49, which motor is pivotally carried on shaft 50, so that it may maintain a driving relation with the gearing upon adjustment of the frame 40 to different heights. The adjustment of the frame 40 to different heights enables the diameter of the shells to be varied.

Supported above the frame 40 with its associated rolls, on standards 51 and brace members 52 is a pusher frame comprising longitudinally extending spaced apart angle bars 53 having toothed racks 59 secured to the top thereof. Suspended from the frame is an arched heat retaining cover 55 having a longitudinal slot along its top. A carriage or trolley comprising frame 56 is mounted on the angle bars, this frame carrying a transverse shaft 57 on which are driving gears 58 for engagement with the racks. Mounted in a plane below gears 58 are rollers 58^a for engagement with the under surfaces of the horizontal flanges of the angle

bars to hold the trolley against vertical movement on the track. At 60 are other guide rollers.

A reversible motor 61 with gearing is mounted on the carriage to drive pinions 58 to propel the carriage back and forth. Extending across the interior of the carriage frame is a transverse fixed bar 62. Pivotedly hung from a cross shaft 63 is a pusher arm 64 having a curved shell engaging portion 73 at its lower end. The upper end of the lever is adapted to contact with bar 62. By this arrangement, the pusher arm is free to swing in the direction of an oncoming shell so as to move out of its way. When, however, the pusher is moved against the rear end of a shell to push the shell in the direction of its travel, through the thrust bearing hereinafter described, rod 62 will form a positive stop to hold the lever against 80 swinging in the direction the push is to be exerted.

Immediately at the end of the receiving table is the thrust bearing for rotatably holding the plug bar and which is so constructed 90 that the plug bar holding means may be released and the pierced shell be passed longitudinally off the bar at the end opposite the plug or ball end.

The thrust bearing includes a supporting pedestal 65, having semi-circular part 66 and semi-circular cap 67 fitting thereon, the cap preferably having an oil box 68 formed on the top thereof. Threaded within the circular opening formed within part 65 and cap 67 is an adjusting sleeve 69 having a hand wheel 70 formed integrally with its rear end, by means of which the sleeve may be turned, a locking sleeve or nut being provided at 71. The interior of the adjusting 105 sleeve 69 is provided with a series of internal ribs and grooves 72, in which are interfitted similar ribs and grooves 73 on the exterior of a hollow slip gear sleeve 74.

The outer end of sleeve 74 is flanged, and surrounding the periphery of the flange is an externally toothed slip ring 75 having internal pockets 76 formed therein, in advance of the annular toothed portion thereof. At 76' are ball bearings which, with the interfitting ribs and grooves, take up the endwise thrust between parts. Slidably supported by the sleeve 74 are clamping jaws 77 adapted to be actuated by pivoted levers 78 pivoted at 79, and having inner ends which are received in pockets in the jaws. The other ends of levers 78 extend into pockets 76. By rotating of the slip gear ring 75 relatively to sleeve 74, while the latter is held stationary, the jaws may be opened or closed, depending upon the direction of rotation of ring 75, the pockets transmitting actuating movement to the jaws through the pivoted levers.

For permitting the ring to rotate with the 130

5 sleeve or independently thereof, I have devised mechanism for this purpose. This mechanism includes a fluid pressure cylinder or jack 80 which operates reciprocable piston rod 81, the outer end of this rod being bifurcated, as shown in Fig. 6. The cylinder is carried on bracket 83 on the pedestal 65.

10 Carried between the two arms of the bifurcated end of the rod is a pinion 84 rotatably mounted on two non-rotatable sleeves 85 and 86, one sleeve being carried by one arm of the bifurcated end and one sleeve by the other arm. Sleeve 85 has a square opening therethrough, and sleeve 86 has a 15 round opening. Interposed between the two sleeves is a series of segmental blocks 87, the outer ends of which extend into an annular groove in the gear wheel 84. The periphery of the series of blocks and the groove may be 20 very slightly eccentric.

Passing through the sleeves is a central pin 88 having a rounded part in sleeve 86, and a squared tapered part 88' passing through the other sleeve 85 and through the 25 opening formed at the center of the series of segments. The length of pin 88 is greater than the combined width of the bifurcated end of the rod, including the stationary arched member 89, through the downwardly 30 turned arms of which the sleeves extend. The taper of the squared part of the pin is toward the center.

Extending from the top of the cylinder is a rigid frame member 90 having downwardly 35 turned flanges to which are formed oppositely extending horizontal slots 91 and 92 terminating at their inner overlapping ends in oppositely inclined cam surfaces 93 and 94, respectively.

40 The ends of the operating levers 78 are permanently received in the pockets 76 and they never ride out of these pockets. The relative rotation between the outer ring 75 and the inner sleeve which supports the operating levers 78 is only such movement as 45 may be imparted to the ring 75 by the reciprocation of the pinion 84 from its retracted to its extended position. This is controlled by the movement of the piston in the 50 cylinder 80 which is a relatively short cylinder. In Figure 5, the closing of the jaws will be effected by the projection of the pinion 84 to the position shown in Figure 4. As the pinion is projected, it is held against 55 rotation, whereupon it tends to rotate the ring 75 a distance corresponding to its reciprocable travel. When the ring 75 moves in this direction, the pockets in the ring, of course, also move. Since the ends of the 60 levers 78 are permanently retained in these pockets, they are rocked to the position shown in Figure 4.

Assuming the parts to be in the position 65 shown in Fig. 6, the projecting end of pin 88 being in groove 91, this is the normal op-

erating position, and the gear ring is rotated with the sleeve through the rotation of the plug bar. The pinion 84 is rotatable, so that it is driven by the gear ring. Now, if the piercing operation has been completed, and it is necessary to open jaws 77, the piston rod is actuated through the cylinder to move rod 81 to retracted position, that is, move it in the direction of the arrow in Fig. 6. Cam surface 91 will force pin 88 70 transversely until the other end of the pin projects into slot 92. As it moves in this manner, segmental blocks 87 are forced outwardly into non-slipping engagement with the recess in the pinion, this recess preferably being slightly eccentric, holding the pinion from rotation. Then, as rod 81 continues to move, the non-rotatable pinion moving with the arm will partially rotate the gear ring to open the jaws. 75

80 When it is desired to close the jaws, the action is just reversed throughout, returning the parts to the position shown in Fig. 6.

85 The operation of the entire machine may now be followed. The ingot passing through the piercing mill is rotated and elongated. Passing over the ball or plug B on the end of bar A, the ingot is pierced to form the shell. During the time the ingot is being pierced, the thrust bearing allows the plug bar and jaws 77 to rotate at the same time that it assumes the end thrust on the bar. With the aid of the power driven troughed feed rollers 45, the shell is advanced until its completed length is on the plug bar and 90 its front end immediately adjacent the jaws 77 of the thrust bearing. 95

100 By means of cylinder 28, the jaws 25 and 25^a may be moved into clamping engagement with the forward end of the plug bar and so held. Jaws 77 of the thrust bearing are then opened in the manner hereinbefore described, the gear ring being rotated relatively to the gear ring sleeve. 105

110 When the jaws 77 are opened, the shell, with the aid of power driven rollers 45, and, if necessary, the overhead pusher including the motor driven trolley, may be passed through the hollow thrust bearing, the jaws 25-25^a holding the plug bar. At the same time, or after the shell has been passed off the plug bar through the thrust bearing, the piston rod 10 is actuated through cylinder 11, sliding head or frame 9, toward the thrust bearing, thus moving the plug bar, engaged by jaws 25-25^a in a corresponding direction, thereby withdrawing the plug or ball B from operative position in the piercing mill, to enable the ball or plug to be replaced. Then the head 9 may be returned to normal position, jaws 77 closed, and jaws 25-25^a opened, whereupon the apparatus is ready to receive the next shell. 115

120 It will be seen that the apparatus, which is relatively simple, is designed to eliminate 125

many of the time consuming operations inherent in present methods, and to greatly facilitate and expedite the piercing and manipulation of pierced shells, and that the apparatus is especially useful in connection with a continuous tube mill.

Various changes and modifications may be made in the structure of the mechanism shown within the contemplation of my invention and under the scope of the appended claims.

I claim as my invention:

1. A thrust bearing for supporting a plug bar comprising a supporting structure, a plug bar engaging means rotatably carried on the supporting structure, said means being movable out of plug bar engaging position whereby a shell may be passed off the plug bar through the thrust bearing.

2. A thrust bearing for supporting a plug bar including a supporting structure, a hollow jaw carrying member rotatably mounted in the supporting structure, and movable jaws on said carrying member, said jaws being movable into and out of plug bar engaging position to permit of the passage of shells through the hollow jaw carrying member.

3. A thrust bearing for supporting a plug bar including a supporting structure, a hollow jaw carrying member rotatably mounted in the supporting structure, movable jaws on said carrying member, said jaws being movable into and out of plug bar engaging position to permit of the passage of shells through the hollow jaw carrying member, and means for operating the jaws.

4. A thrust bearing for supporting a plug bar including a supporting structure, a hollow jaw carrying member rotatably mounted in the supporting structure, movable jaws on said carrying member, said jaws being movable into and out of plug bar engaging position to permit of the passage of shells through the hollow jaw carrying member, and power driven means for operating the jaws.

5. A thrust bearing comprising a supporting structure, a rotatable sleeve carried in said structure, transversely movable jaws carried by the sleeve, a gear ring rotatably mounted on said sleeve, means connecting the gear ring and jaws for moving the latter upon rotation of the former relatively to the sleeve, and means for effecting the relative rotation of the ring.

6. A thrust bearing comprising a supporting structure, a rotatable sleeve carried in said structure, transversely movable jaws carried by the sleeve, a gear ring rotatably mounted on said sleeve, means connecting the gear ring and jaws for moving the latter upon rotation of the former relatively to the sleeve, means for effecting the relative rotation of the ring, including a pinion in

mesh with the gear wheel, means for reciprocating the pinion, and means for locking the pinion against rotation when reciprocated in one direction and releasing it when it is moved in the opposite direction.

70

7. A thrust bearing comprising a supporting structure, a rotatable sleeve carried in said structure, transversely movable jaws carried by the sleeve, a gear ring rotatably mounted on said sleeve, means connecting the gear ring and jaws for moving the latter upon rotation of the former relatively to the sleeve, and means including a reciprocable toothed member and operating means therefor for effecting the movement of the gear ring relatively to the sleeve.

8. A thrust bearing comprising a supporting structure, a rotatable sleeve carried in said structure, transversely movable jaws carried by the sleeve, means providing a bearing for the sleeve, said bearing means being longitudinally adjustable, a gear ring rotatably mounted on said sleeve, means connecting the gear ring and jaws for moving the latter upon rotation of the former relatively to the sleeve, and means for effecting the relative rotation of the ring.

9. The combination with a rotatable thrust bearing for supporting a plug bar, said bearing having jaws movable into and out of operative position to permit of the passage of shells through the bearing, of means disposed in advance thereof including a support, plug bar engaging jaws on the support, and means for operating said second jaws, the second jaws enabling the plug bar to be supported when the thrust bearing jaws are opened.

10. The combination with a rotatable thrust bearing designed to permit of the passage of shells therethrough, and having plug bar engaging jaws thereon movable into and out of plug bar engaging position, of a plug bar, and a supporting structure having plug bar engaging jaws for engagement with the forward portion of said plug bar, said jaws being movable into and out of bar engaging position, whereby the front end of the bar may be held when the jaws of the thrust bearing at the rear end of the bar is released.

11. The combination with a rotatable thrust bearing designed to permit of the passage of shells therethrough, and having plug bar engaging jaws thereon movable into and out of plug bar engaging positions, of a plug bar, and a supporting structure having plug bar engaging jaws for engagement with the forward portion of said plug bar, said jaws being movable into and out of bar engaging position, and power driven operating means for said second named jaws, whereby the front end of the bar may be held when the jaws of the thrust bearing at the rear end of the bar is released.

120

125

130

12. The combination with a rotatable thrust bearing designed to permit of the passage of shells therethrough, and having plug bar engaging jaws thereon movable into and out of plug bar engaging positions, of a plug bar, and means for releasably supporting the forward end of the bar, whereby the bar may be supported when the jaws of the thrust bearing are released.

13. The combination with a thrust bearing designed to permit of the passage of shells therethrough, and having plug bar engaging jaws thereon movable into and out of plug bar engaging positions, of a plug bar, and means for releasably supporting the forward end of the bar, whereby the bar may be supported when the jaws of the thrust bearing are released, said supporting means being reciprocable longitudinally of the plug bar, and means for effecting such reciprocation.

14. The combination with a thrust bearing designed to permit of the passage of shells therethrough, and having plug bar engaging jaws thereon movable into and out of plug bar engaging positions, of a plug bar, and a supporting structure having plug bar engaging jaws for engagement with the forward portion of said plug bar, said jaws being movable into and out of bar engaging position, means for operating the second jaws, whereby the front end of the bar may be held when the jaws of the thrust bearing are open, and means for effecting longitudinal reciprocation of the said second jaws to reciprocate the plug bar.

15. The combination with a rotatable thrust bearing for use in connection with piercing mills for supporting the rear end of a plug bar, said thrust bearing being designed to permit of the passage of pierced shells therethrough and having jaws movable into and out of plug bar engaging position, of a plug bar, means near the forward end of the plug bar for releasably holding it, and a receiving table interposed between the front plug bar engaging means and the thrust bearing.

16. The combination with a rotatable thrust bearing for use in connection with piercing mills for supporting the rear end of a plug bar, said thrust bearing being designed to permit of the passage of pierced shells therethrough and having jaws movable into and out of plug bar engaging position, of a plug bar, means near the forward end of the plug bar for releasably holding it, and a receiving table interposed between the front plug bar engaging means and the thrust bearing, said receiving table having power driven feed rolls associated therewith to assist in moving a shell along the plug bar toward and through the thrust bearing.

17. The combination with a thrust bearing for use in connection with piercing mills

for supporting the rear end of a plug bar, said thrust bearing being designed to permit of the passage of pierced shells therethrough and having jaws movable into and out of plug bar engaging position, of a plug bar, means near the forward end of the plug bar for releasably holding it, and a receiving table interposed between the front plug bar engaging means and the thrust bearing, said receiving table having a trolley associated therewith movable therealong, and which carries a pusher for engaging the ends of the shells and pushing them in the direction of their travel.

18. The combination with a thrust bearing for use in connection with piercing mills for supporting the rear end of a plug bar, said thrust bearing being designed to permit of the passage of pierced shells therethrough and having jaws movable into and out of plug bar engaging position, of a plug bar, means near the forward end of the plug bar for releasably holding it, a receiving table interposed between the front plug bar engaging means and the thrust bearing, said receiving table having power driven feed rolls thereon for engaging the shells, and a reciprocable pusher mechanism associated with the receiving table.

19. The combination with a thrust bearing for use in connection with piercing mills for supporting the rear end of a plug bar, said thrust bearing being designed to permit of the passage of pierced shells therethrough and having jaws movable into and out of plug bar engaging position, of a plug bar, means near the forward end of the plug bar for releasably holding it, and a receiving table interposed between the front plug bar engaging means and the thrust bearing, said receiving table having a shell receiving guideway, said guideway being adjustable vertically for accommodation of shells of different diameters.

20. The combination with a thrust bearing for use in connection with piercing mills for supporting the rear end of a plug bar, said thrust bearing being designed to permit of the passage of pierced shells therethrough and having jaws movable into and out of plug bar engaging position, of a plug bar, a support disposed near the front end of the plug bar, means for reciprocating said support longitudinally of the plug bar, jaws on said support movable into and out of plug bar clamping position, means for operating the jaws, a receiving table interposed between the front support and thrust bearing, said receiving table having power driven shell feeding mechanism thereon, and guide means on the table extending in advance of the table and slidably supported on said reciprocable jaw carrying supports.

In testimony whereof I affix my signature.
JAMES J. HARKINS.
